G. F. RENDALL,
COMBINED GAS PRODUCER AND SUPERHEATER,
APPLICATION FILED JUNE 29, 1917,

1,366,213.

Patented Jan. 18, 1921.

INVENTOR

George F. Kendall,
BY Wellesley Fairbanks,
ATTORNEYS.

UNITED STATES PATENT OFFICE.

GEORGE F. RENDALL, OF NEW YORK, N. Y., ASSIGNOR TO CARBON PRODUCTS COMPANY, A CORPORATION OF DELAWARE.

COMBINED GAS-PRODUCER AND SUPERHEATER.

1,366,213.

Specification of Letters Patent. Patented Jan. 18, 1921.

Application filed June 29, 1917. Serial No. 177,672.

To all whom it may concern:

Be it known that I, GEORGE F. RENDALL, a citizen of the United States, residing in the city and county of New York, State of New York, have invented a new and useful Combined Gas-Producer and Superheater, of which the following is a specification.

My invention comprehends a gas producer or retort of novel construction more particularly adapted for use in conjunction with the structure of my previous patent on apparatus for producing gas, #903,503, patented November 10th, 1908.

One object of my invention is to provide a novel gas producer wherein a superheater is located in the combustion chamber or retort of the gas producer to utilize the generated gases in the combustion chamber to superheat steam supplied to the superheater from without the producer.

A still further object of my invention is to provide a coil of superheated pipes in the combustion chamber of the gas producer, together with means for discharging the superheated steam in an equally distributed atomized volume through a bed of live carbonaceous material in the combustion chamber to mix with the gases generated from the carbonaceous material contained in the combustion chamber.

Another object of my invention is to provide a gas producer consisting of a combustion chamber and a steam chamber in communication with each other, a superheater in the combustion chamber, a discharge pipe of the superheater leading from the combustion chamber to the steam chamber said pipe being provided with a nozzle on one end thereof to direct said superheated steam downward against the bottom of the steam chamber to thoroughly atomize the superheated steam and also equally distribute the volume of steam in passing upward through a bed of live carbonaceous material.

Another object of my invention is to provide a gas producer or retort of this character whereby the superheated steam generated in said retort is utilized to cause a suction draft in said furnace to promote combustion, also means for controlling said draft to most efficiently effect combustion of the carbonaceous material contained in said retort.

For the purpose of illustrating my invention, I have shown in the accompanying

drawing one form thereof which is at present preferred by me, since the same will be found in practice to give satisfactory and reliable results, although it is to be understood that the various instrumentalities of which my invention consists can be variously arranged and organized and that my invention is not limited to the precise arrangement and organization of these instrumentalities as herein shown and described.

The figure shown represents a view partly in section and side elevation of a gas producer in connection with a condenser.

Similar numerals of reference indicate corresponding parts in the figure.

Referring to the drawing.

The gas producer 1 may be constructed to stand either upright as shown in the drawing or it may extend horizontally to suit various conditions, and is preferably constructed of a suitable refractory material 3, such as firebrick or the like, which is enclosed by the metallic casing 4. 5 designates the furnace or combustion chamber and 6 designates grate bars in the lower portion thereof separating the furnace from the steam chamber 7 below. The top of the furnace is closed by the cover plate 8 provided with a suitable feeding or stoking mechanism 9, whereby any desired fuel such as coal or other carbonaceous material may be automatically or otherwise fed into the furnace 5 upon the grate bars 6. 10 designates a discharge pipe, stack or chimney leading from the furnace 5 of the gas producer which is provided with suitable draft controlling mechanism 11 whose detailed construction need not be described. 12 designates a pipe or conduit leading from the discharge pipe 10 intermediate the producer 1 and the valve mechanism 11, the same discharging into the chamber 13 of the condenser 2.

14 designates an apertured plate at the upper end of the condenser 2 in the apertures of which are located the ends of the pipe 15. It will of course be understood that a similar apertured plate is provided at the lower end of the condenser thus forming an air chamber 16 within the condenser 2. The air chamber 16 communicates by means of the pipe 17 provided with a suitable controlling valve 18, with the steam injection pipe 19 having a controlling valve 20 therefor. The steam injection pipe 19 discharges

into the steam chamber 7 of the producer and the waste steam from the pipe 19 is discharged into the discharge pipe 10 by means of the upwardly extending pipe 21 provided with the valves 22 and 23 for controlling the steam supply for draft purposes to the discharge pipe 10 from the steam injector pipe 19 and the steam superheater 24 located within the furnace 5 of the producer to be more fully described in detail hereinafter.

25 designates a conduit leading from the condenser 2 and communicating with the pipes 15 in said condenser. The conduit 25 discharges into a scrubber (not shown) 15 which comprises a container for a suitable alkaline material such as caustic soda, in order that the oxid contained in the gas will combine therewith and remove therefrom the inert compounds such as carbon dioxid.

20 The gas after passing from the scrubber is ignited and combined with a suitable proportion of oxygen prior to passing into a furnace or retort (not shown) which contains iron turnings, filings or other metallic material adapted to be heated to a high heat so that the gas passing into and through said retort will be oxidized in such a manner that substantially all the inert contents of the gas will be removed whence the gas in 30 its purified state may be led to a desired point of utilization.

The scrubber, retort and other adjuncts may be of any desired construction and arranged preferably to conform with that 35 shown in my Patent #903,503, heretofore referred to, and it is therefore not necessary to describe the same in greater detail.

40 The steam superheater 24 located within the combustion chamber or retort 5 of the gas producer forms the principal feature of my present invention and consists of the supply pipe 26 in communication with any suitable source of steam preferably not superheated. The pipe 26 is provided with the 45 valve 27 for the control of the supply of steam to the coils 28 of the superheater. 29 and 30 designate discharge pipes from the superheater 24, the pipe 29 discharging superheated steam through the nozzle 31 50 against the heated bed 32 of the chamber 7 to cause the steam to be directed upward in an equally distributed atomized condition to pass through the bed of live carbonaceous material supported on the grate 6 to form 55 an admixture of the superheated steam and the gases generated from the carbonaceous materials. This admixture of superheated steam and generator gases is then passed from the producer 1 through the pipes 10 60 and 12 into the condenser thence into the scrubber (not shown) and the metal containing retort or furnace (not shown) to bring the gas into its purified state.

65 The discharge pipe 30 from the superheater discharges into the pipe 21 in com-

munication with the gas discharge pipe or chimney 10. The pipe 21 is controlled by the valve 23 for the supply of steam to said chimney 10 to cause a suction or draft in the retort 5 to promote combustion of the materials contained therein.

70 33 designates an exhaust pipe for the exhaust of excess superheated steam from the superheater 24, said pipe 33 being provided with a valve 34.

75 In the operation of my novel gas producer steam is supplied in a nonsuperheated state from without the producer by the pipe 26 to the superheater 24 located in the retort 5 whereupon the steam becomes superheated 80 by the heat from the combustion of the carbonaceous materials in the furnace. By the discharge pipe 29 steam is led from the superheater 24 to the lower steam chamber 7 where the superheated steam is thoroughly 85 atomized before passing through the bed of live carbonaceous material on the grate 6 so that said superheated steam thoroughly mixes with the gases generated from the carbonaceous materials to form an admixture 90 of superheated steam and gases.

95 This admixture of superheated steam and gases is then discharged through the pipes 10 and 12 into the condenser where the admixture is condensed preparatory to passing into the scrubber (not shown) and metal containing retort (not shown) to complete the process of purifying the gases.

100 To promote combustion in the retort 5 a draft regulator 11 is provided in the chimney 10 and above the draft regulator 11 an inlet from the pipe 21 is arranged to allow for the discharge of superheated steam into the chimney to cause an upward suction or draft from the retort 5, it being apparent 105 that the opening of the valve 23 permits steam to flow through the pipe 30 to the pipe 21 and thence into the upper portion of the stack or chimney 10 for the purpose described.

110 It will now be apparent that I have devised a novel and useful construction of a combined gas producer and superheater which embodies the features of advantage 115 enumerated as desirable in the statement of the invention and the above description, and while I have, in the present instance, shown and described a preferred embodiment thereof which will be found in practice to give satisfactory and reliable results, it is to be 120 understood that the same is susceptible of modification in various particulars without departing from the spirit or scope of the invention or sacrificing any of its advantages.

125 Having thus described my invention, what I claim as new and desire to secure by Letters Patent, is:—

130 In a device of the character stated, a gas producer, a combustion chamber therein, a grate in the lower portion thereof, a bed be-

low said grate forming a steam chamber between said bed and said grate, a steam superheating coil in said combustion chamber, a discharge pipe from said superheating coil 5 terminating in a downwardly deflected nozzle discharging superheated steam downwardly against said bed prior to its passage upwardly through the incandescent carbonaceous materials in said combustion chamber, 10 a condenser, a passage leading from said condenser to said steam chamber for con-

veying heated air thereto, a branch from said superheating coil discharging superheated steam into said passage, and a conduit leading from said gas producer to said condenser, for conveying superheated steam and gases thereinto. 15

GEORGE F. RENDALL.
